[57] ABSTRACT

A by-pass canal of a cooling system in an internal combustion engine for bypassing a cooling liquid between a thermostat and a liquid pump in a shortcircuit. The by-pass canal is formed in a cylinder, and a cylinder head of the engine or formed in a cylinder, a cylinder head and a crank case of the engine without extending outside of the engine.

COOLING SYSTEM IN A LIQUID COOLED INTERNAL COMBUSTION ENGINE

This is a division, of application Ser. No. 199,400, filed Oct. 21, 1980, now U.S. Pat. No. 4,382,426.

SUMMARY OF THE INVENTION

The present invention relates to a liquid-cooled internal combustion engine, and more particularly it is concerned with a by-pass circuit of a cooling system.

In the cooling system of the liquid-cooled internal combustion engine a by-pass circuit is provided for preventing super cooling of a cooling liquid.

The by-pass circuit in the prior art has been provided with a rubber hose separately formed from an engine body and connected with a thermostat and a liquid pump for forming a short circuit. The by-pass circuit of the prior art has been formed as a separate part, so that it is difficult to avoid positively the leak of the liquid from the connecting part. And the piping of the prior art has been troublesome and injured the appearance of the engine body.

An object of this invention is to provide a by-pass circuit which is free from the aforesaid disadvantages of the prior art.

This invention provides a cooling system having a by-pass circuit constructed in the engine body in one body.

BRIEF DESCRIPTION OF THE DRAWINGS

PRIOR ART

FIG. 1 is a left side sectional view of the internal combustion engine having the by-pass circuit of the prior art;

FIG. 2 is a schematic rear view of the engine in FIG. 1 in which the by-pass circuit is shown in a sectional view taken along a line II—II in FIG. 1;

FIG. 3 is a left side sectional view of the embodiment of the prior art;

FIG. 4 is a schematic rear view of the embodiment shown in FIG. 3;

FIG. 5 is a schematic left side view of the internal combustion engine according to the present invention;

FIG. 6 is a rear view of the engine shown in FIG. 5 with partial fragmentary section taken along a line VI—VI;

FIG. 7 is a sectional view taken along a line VII—VII in FIG. 6;

FIG. 8 is a partial side view of the second embodiment of the present invention;

FIG. 9 is a rear view of the embodiment shown in FIG. 8; and

FIG. 10 is a sectional view taken along a line X—X in FIG. 8.

DETAILED DESCRIPTION OF THE PREFERRED EMBODIMENT

At first the prior art will be explained by referring to the accompanying drawings.

In FIGS. 1-4 a by-pass circuit is formed with a hose connecting between a thermostat and a liquid pump. In FIG. 1 a cylinder head 1, a cylinder case 2 and a crank case 3 are connected with each other in one piece and provide an internal combustion engine body. A gear case 4 is mounted on a side wall of the crank case 3. A gear rotatably supported in the crank case (not shown in the drawing) engages with a gear supported on a crank

shaft 5 and transmit a rotary motion to an impeller in a liquid pump 6 connected to the gear case 4. An inlet 7 of the liquid pump 6 is connected with an outlet of a radiator R (FIG. 5) through a rubber hose 8. A by-pass joint 9 disposed nearer to the suction impeller than to the inlet 7 of the pump is connected with a thermostat at an inlet thereof for the by-pass through a by-pass hose 10 and a by-pass joint 11. 13 designates an outlet of the liquid pump 6 and the outlet is connected with a cooling water canal 14 at a connecting portion between the liquid pump 6 and the crank case 3. The cooling liquid canal 14 is connected with a jacket (cooling liquid canal) in the cylinder case 2 at another side of the crank case 3. An outlet 15 of the thermostat 12 is connected with the inlet of the radiator through a rubber hose 16. 17 designates a carburetor, 18 designates an ignition plug and 19 designates a clamp ring. In FIG. 2 20 designates a liquid outlet of by-pass circuit, and 21 designates a liquid inlet of the by-pass circuit.

When the temperature of the cooling liquid is lower than the predetermined temperature as in warming up just after the starting and so on the canal between the liquid jacket in the cylinder head 1 and the outlet 15 is shut off by the thermostat 12. The liquid flows therefore from the outlet 13 of the liquid pump to the inlet thereof through the cylinder case 2, the cylinder head 1 and the by-pass hose 10 and does not flow through the radiator. The cooling liquid is pressed in the pump and recirculated from the outlet 13 to the cylinder case 2 and cylinder head 1 and the temperature of the liquid is raised rapidly. When the temperature of the cooling liquid rises over the predetermined temperature the thermostat is opened and the cooling liquid in the cylinder head 1 is fed to the radiator through the outlet 15 of the thermostat and the rubber hose 16. The cooling liquid is cooled in the radiator and then returned to the liquid pump 6 through the rubber hose 8 and the inlet 7. The liquid pressed in the pump 6 is fed to the cylinder head 1 through the outlet 13 and the cylinder case 2.

In FIGS. 3 and 4 another embodiment of the prior art is illustrated. In these figures identical reference numerals are utilized to refer to like elements in FIGS. 1 and 2, the liquid pump 6 is mounted to the cylinder case 2 and the by-pass hose 10 is elongated in a space between the carburetor 17 and the cylinder case 2 in substantially horizontal.

In the prior art the by-pass canal connecting between the thermostat and the liquid pump for shortcircuiting has been formed with a by-pass hose 10 in separate form. Therefore the following disadvantages can be cited. (1) The piping of the rubber hose is complicated. (2) At the connecting portion of the rubber hose the leak cannot be prevented positively. (3) A large number of parts has been required and the by-pass circuit of the prior art has been expensive. (4) The rubber hose has been disposed outside of the engine body, so that the feature is injured.

The present invention dissolves the above mentioned disadvantages by providing the by-pass canal in the cylinderhead and the cylinder case in one body or in the cylinder head, the cylinder case and the crank case in one body.

One embodiment of the present invention is illustrated in FIGS. 5 to 7. In FIG. 6 a by-pass canal 22a formed in the cylinder head 1 is connected in liquid-tight with a by-pass canal 22b formed in the cylinder case 2 in a joining plane between the cylinder head 1,

and the cylinder case 2, and the by-pass canal 22b is connected in similar manner with a by-pass canal 22c in the crank case 3 in a joining plane between the cylinder case 2 and the crank case 3. The by-pass canal 22c is connected in liquid-tight with a by-pass canal 22d in the liquid pump by using O-ring 26 in a fitting plane of the crank case 3 for the liquid pump 6. The by-pass canal 22d is formed in a cylindrical part being formed in one body with a casing of the liquid pump 6. A flange 27 formed at one end of the cylindrical part 27 is screwed to the common fitting plane 25 of the crank case together with a flange 29 of an outlet 13. The O-ring 26 is inserted in an annular groove formed in the flange 28. 30 designates a connecting pipe. The connecting pipe connects the cooling liquid canal 14 in the crank case 3 with a cooling canal 31 in the cylinder case 2 (FIG. 7). The by-pass canals 22a, 22b and 22c in FIG. 6 are formed in one canal simultaneously by securing the cylinder head 1, cylinder case 2 and crank case 3 each other with a plurality of bolts. The by-pass canals 22c and 22d are connected with each other by securing the liquid pump 6 to the fitting plane 25 of the crank case with a plurality of bolts. The flow direction of the cooling liquid is similar to that of the prior art. When the temperature of the cooling liquid is lower than the predetermined temperature, the cooling liquid in the cylinder head 1 bypasses to the liquid pump 6 through the by-pass canals 22a to 22d and the flow of the cooling liquid in the 30 cylinder head 1 is changed to the circuit through the radiator R by rising of the liquid temperature over the predetermined temperture.

In a second embodiment illustrated in FIGS. 8 to 10 a by-pass canal 22a of a cylinder head 1 is connected with a by-pass canal 22d' in a liquid pump 6' only through a by-pass canal 22b' in a cylinder case 2.

In the present invention the by-pass canal is formed within each wallthickness of the cylinder head, the cylinder and the crank case, so that the by-pass canal is formed inside of the engine body and do not extend outside of the engine body and the feature of the engine body can be elevated.

In the internal combustion engine with multicylinder 45 it is not necessary to dispose the hose or pipe in an intricated space by mounting the carbureters and so on,

so that the design of the engine can be facilitated in the present invention.

In the present invention the connection of the rubber hose and so on is unnecessary, so that the leak of the liquid can be avoided.

In the present invention the number of the parts can be decreased and the expenses can be cut down.

What is claimed is:

1. A cooling system for an internal combustion engine comprising:

an engine section including a cylinder head, a cylinder case and a crank case to contain a plurality of reciprocating pistons and a liquid passage for cooling the engine section by liquid flowing in the passage, said pistons being disposed in said engine section parallel to each other,

pump means situated outside said engine section, said pump means forcibly transmitting liquid into said liquid passage in said engine section to cool said engine section,

thermostat means connected to said cylinder head between the two adjacent pistons, said thermostat means being connected to said liquid passage in said engine section so that the liquid pumped by said pump means flows out through said thermostat means,

a radiator connected between said thermostat means and said pump means to cool the liquid from the engine section and to supply the cooled liquid again to the engine section by means of said pump means, and

a by-pass canal integrally formed inside said engine section for internally connecting said pump means and said thermostat means so that when the liquid passing through said liquid passage in the said engine section is cool, the liquid is transmitted to the pump means through said by-pass canal without passing through the radiator.

2. A liquid cooling system according to claim 1, in which said by-pass canal extends downwardly through the cylinder case to the pump means.

3. A liquid cooling system according to claim 2, in which said pump means is situated in the front end of the cylinder case of the engine section, said by-pass canal substantially horizontally extending in the cylinder case.
